HEAT-SEALING WRAPPING MACHINE

George Arlington Moore, New York, N. Y.

Application October 14, 1948, Serial No. 54,437

9 Claims. (Cl. 53—25)

1

The present invention relates to heat-sealing wrapping machines, particularly adapted for producing filled packages of cigarettes in a single composite wrapper of foil laminated paper and in such manner that a superior package results, with such complete sealing of the seams and folds that the cigarettes are protected more effectively than by the packages now in general use.

A wrapper particularly adapted for use in the machine is a cut section of a duplex sheet material, which may be fed from a roll thereof, and comprising aluminum foil bonded on one surface to a sheet of paper, the foil having a pattern at longitudinal seam and end fold areas consisting of a normally dry heat-sealing material. Such a wrapper is, from its physical standpoints, ideally adapted to protect the contents of the packages, but involves many problems arising through high speed machine operations at the various stages, and where, for example, an operation must be performed in a fraction of a second, where wrapper sheet sections must be accurately measured, cut from the roll, and positioned, whilst the feed from the roll is uninterrupted, and this in a fraction of a second, and where an assembly of cigarettes is forcibly projected against the newly formed folds of a bottom of a package, for ejection of the package, under conditions where the folds must be tacked resistant to such action in a small fraction of a second, etc., etc.

The invention also relates to a method of packaging upon which method the machine is based.

The invention will be described with reference to the accompanying drawings, in which:

Fig. 1 is a schematic view in elevation showing at the left a cigarette-receiving turret and at the right a wrapper-forming turret, with web feeding and cutting elements above the latter;

Fig. 1a is an enlarged section taken generally on the line 1a—1a, Fig. 1, showing the transfer of cigarettes into a wrapper held by an arbor of the wrapping turret;

Fig. 1b is an enlarged sectional view taken on the line 1b—1b, Fig. 1 showing the bottom fold tacking step preliminary to the transfer of cigarettes to the package wrap;

Fig. 1c is a view in elevation showing the filled package on a support after ejection from the turret, the top closure folding tools being in position for closing the end folds only;

Fig. 2 is a view in front elevation, partly broken away, showing an embodiment of the invention;

Fig. 3 is a view in elevation taken at right angles to Fig. 2 and showing the delivery end of the machine;

Fig. 4 is a section taken generally on the line 4—4 of Fig. 2 (as to the wrapper web) showing the electric eye beam arrangement;

Fig. 5 is a schematic perspective view showing

5 a section of the web containing a signal spot for the electric eye scanning devices;

Fig. 6 is a sectional elevation showing the drive shaft for the web feeding mechanism and the elements which actuate the same independently through a planetary gear from a motor which will be energized through the action of the photo-electric mechanism;

Fig. 7 is a fragmentary elevation, partly in dotted line taken along the line 7—7, Fig. 6;

Fig. 8 is an enlarged fragmentary view showing a section of the wrapping turret at which the wrapper is acted upon by side seam tools;

Fig. 9 is a schematic view partly in section showing the action of the bottom flap folding tools;

Fig. 10 is a view in elevation somewhat enlarged with respect to Fig. 8, and showing the position of a side seam heating iron after withdrawal of the body folding tuckers forming part of the side seam mechanism;

Fig. 11 is a view in elevation taken at right angles to Fig. 10 and showing the same instrumentalities, with a side seam iron down;

Fig. 12 is a view similar to Fig. 11 showing a side seam iron retracted;

Fig. 13 is a view partly in section showing a body clamp assembly including its support and its movable clamp plate;

Fig. 14 is a schematic view showing the bottom end fold tuckers, with respect to their action preliminary to the action of the side folding tool shown in Fig. 9;

Fig. 15 is a composite view in perspective showing the manner of folding the wrapper body;

Fig. 16 is a view similar to Fig. 15 showing the successive folding of the bottom flaps;

Fig. 17 is a plan view of a wrapper blank showing by stipple the adhesive pattern and by dotted lines the transverse lines of fold;

Fig. 18 is a general wiring diagram;

Fig. 19 is a schematic view in top plan taken generally on the line 19—19, Fig. 3;

Fig. 20 (at the right hand side of Fig. 3) is a detail rear elevation of the chill and discharge elements;

Fig. 21 is an enlarged transverse section taken generally on the line 21—21, Fig. 2, showing the package transfer initial to active movement;

Fig. 22 is a view similar to Fig. 20 showing the package transfer at the end of an active movement;

Fig. 23 is a detail view in elevation taken at right angles to Fig. 21, and generally on the line 23—23, Fig. 21;

Fig. 24 is a view in elevation taken at right angles with respect to Figures 21 and 22 to further illustrate the transfer mechanism;

Fig. 25 is an enlarged detailed view showing 60 elements of the knife actuating mechanism, the

view being taken at right angles to Figure 6, generally on the line 25-25 of that figure;

Fig. 26 is a plan view of the web cutting knife and its immediate actuating members;

Fig. 27 is a vertical section on the line 27-27, Fig. 3;

Fig. 28 is a vertical section on the line 28-28, Fig. 3;

Fig. 29 is a view in elevation of the electric eye circuit cam controlled ground switch.

Referring to Figures 1 and 2 of the drawings, it will be seen that the wrapper web is fed from a roll 1 to a guide roller 2, which acts as a tension member, thence over a roller 3 carried by swinging arm 4 mounted to swing about a shaft 5. At the end of swinging arm 4 are two rollers 6x and 6. Roller 6 is a positively acting feed roller which is driven by a chain belt 7 from a sprocket wheel on shaft 5, the latter being indicated by the dotted lines 8.

Arm 4 is swung downwardly and upwardly about shaft 5 by any suitable means, as for example, a crank or cam arrangement (not shown) on shaft 16 (Fig. 6), and at an upward speed equivalent to the feeding action of roller 6, whereas in the downward movement of the arm there is a feeding action and also a pushing action upon the web which projects below the rollers 6x and 6.

A sprocket wheel 9, Fig. 6, is loosely mounted on shaft 5 and its hub carries a gear 18 which is rotated by the action of a chain belt 10 leading to a sprocket wheel on the shaft 11 of a motor 12.

The web is cut into sheet sections by a knife 13 which co-acts with a fixed blade 14 (Fig. 1). This knife is thrown into action at the proper time by the means illustrated in Figures 6 and 25, 26. Reference to those figures will show that knife 13 is carried by an arm 13x which forms one arm of the bell crank, the latter having its hub carried by a shaft 14 supported in a bearing sleeve 15, the second arm of the bell crank arrangement, indicated at 13xx carrying a roller in the active channel of a cam 15.

The control for accurate cut sheets

Inasmuch as the wrappers are intended to form the outside of the packages and will customarily be printed in a manner requiring an exact placement of the line of cut at which the sheet is separated from the web, provisions are made for exact registration of the point at which the web is cut, throughout the feed thereof. Reference to Figures 6 and 7, in conjunction with Fig. 5 and also Figures 25 and 26, will show that the knife actuating cam 15 is mounted on a shaft 16, that shaft carrying a pinion 17 driven by the gear 18 on shaft 5. Loosely mounted on shaft 5 is a large sprocket wheel 19 which rotatably carries the small gears 20 of a planetary gear assembly which includes internally toothed planetary gear 21 in mesh with which are the gears 20. The gears 20 also are in mesh with a gear 22 keyed to the shaft 5.

The large sprocket wheel 19 is driven by a chain belt 23 leading to a sprocket on motor shaft 11 (Fig. 2).

Member 21 of the planetary gear arrangement is normally held motionless in the following manner: The said gear 21 carries a worm wheel 24 engaged by a worm 25 on a shaft 26, the latter carrying a sprocket wheel 27, driven by chain belt 28, from a motor (not shown). Thus rotation of sprocket wheel 19 will compel rota-

tion of the small gears 20 relatively to the internal teeth of planetary member 21 and this will compel rotation of gear 22 fixed to shaft 5. The rotation of the latter will cause active movement of the web feed (as hereinabove described).

Except for slippage and hence short feed there is no difficulty. The problem to be overcome is periodic slippage and hence short feeding. Referring to Figure 5 the web is indicated at W and it will be noted at Wx that a signal spot is shown, which will be one of a series exactly spaced throughout the web. These signal spots are adapted to provide an interruption or contrast in light refraction from a beam generating element indicated at 30, Fig. 4, and a beam receiving element 31, the two constituting photoelectric cell elements.

The knife-actuating cam always throws the knife into action at a predetermined point of rotation of the cam-shaft 16, Fig. 6 and 26.

The electric eye device is in positive condition for throwing into action the motor and drive elements for member 21 of the planetary assembly, until the beam of light reaches the signal spot Wx on the web. That signal spot renders the electric eye momentarily ineffective. The electric eye device also is ineffective when the web feed is accurate, because of the action of a cut-out switch. The switch is shown in Fig. 29.

Referring to Fig. 29, it will be seen that the contacts are normally closed and hence the signal from the electric eye passing, for example, from ground wire 24 to the switch, will be grounded via 35. When, however, cam 32 opens switch arm 33, the electric eye signal will not be grounded but will occur as a positive impulse to the motor control for member 21 of the planetary assembly. In normal and accurate feeding stages of the web, cam 32 will open the switch and hold it open during registration of the beam of light with signal spot Wx. Inasmuch as the electric eye has no action while the beam of light is on the signal spot, member 21 of the planetary assembly remains motionless. If, however, the feed of the web is short at the time, just prior to cutting of the web, and when switch-arm 33 is held open by the cam, the signal spot will not have reached the beam of light, and immediately the motor and drive elements for member 21 of the planetary assembly will give a quick feeding impulse to the web, bringing the signal spot Wx into registration with the beam of light before the switch contacts are closed. At that instant the knife is mechanically actuated and the web accurately cut.

The sheet when cut will lie in the position of Fig. 1 and immediately prior thereto the package P₂ at the top of the wrapping turret will have been ejected. Thus at the instant of cutting a body clamp 36 will be moved to the left and the wrapper sheet will be partly folded around the arbor 37 as shown at the upper right hand portion of Fig. 1.

Preliminary outline of operation sequences

At this point an outline of the operation sequences will be helpful for better understanding of the more detailed description later to be given herein. Referring to Fig. 1 it will be understood that at the stage indicated at C in that figure, the wrapper has been partly folded about an empty arbor of the wrapping turret through the conjoint action of the arbor and a clamp plate, the wrapper engaging three sides of the arbor. The arbor is then advanced to the body folding

station D where tuckers act first at the left and then at the right of the arbor to overlap the margins of the wrapper which margins are then engaged by an electrically heated lap iron after sufficient retraction of the tuckers. The lap iron imparts heat to the wrapping material at such overlapped area as to activate thermoplastic material carried by the under face of the wrapper thereby forming a bonded longitudinal seam. The lap iron remains in engagement with the longitudinal seam through a plurality of the successive stages. At stage E tools form the bottom closure, and as the turret advances the bottom closure folds are engaged at stage G with tools including an electrically heated plate, that tack the bottom folds to semi-seal them. The tacking is done in two stages; first, a plunger enters the arbor at the inside of the closure folds, and secondly, an electrically heated iron compresses the folds against the plunger, imparting heat to lightly activate the thermoplastic adhesive.

The time permitted for the semi-sealing of the bottom closure folds is very short. For example, in commercial operation the wrapping turret assembly may form and fill 125 packages per minute, and the semi-sealing action upon the bottom folds will be less than $\frac{1}{6}$ of a second.

At stage A the package with its bottom fold semi-sealed comes into register with an arbor charged with cigarettes and the cigarettes are transferred to the package, the latter still having an open top. The filled package is then moved to station B, at which station a plunger enters the package arbor and pushes the cigarettes forwardly, thus stripping the package and its contained cigarettes from the arbor and into a trough. While in motion in said trough the top mouth of the package is engaged by folding tools to form the top closure, and in their advance, the packages meet a heated tacking iron which flattens down the top closure folds and lightly tacks them with heat. In such movement the packages lie horizontal. They are then transferred from the trough to upright position with the top closure uppermost and pass through the well known revenue stamp application.

From the revenue stamp applicator, the package reaches a sealer which comprises a pair of thin steel belts, one belt engaging the bottom of the package and the other belt engaging the top of the package. This sealer is independently driven and runs continuously regardless of the machine proper, and the speed is regulated to carry the packages without interference from packages ejected from the stamp applicator assembly. At the end of the belt sealer, the steel belts being electrically heated, is a final sealing and "chill" assembly which consists of upper and lower air cooled metallic trough members adapted to apply major pressure along an intermediate area of the top and bottom closure folds for better sealing, as compared with the action of flat plates. This completes the sequence of operation.

The sealer provides a relatively long time interval throughout which the adhesive is maintained heated and therefore plastic, so that the pressure of the heated metallic belts and their vibration rearranges the top and bottom folds into complete and tight sealing contact which is completed by the "chill" assembly. It will be understood while the opposed heated metallic belts will impose pressure upon the ends of the packages, this pressure will be substantially less than that which would deform the circuit ends.

The body folding tuckers and the pre-acting clamping plate

Referring to Figures 10 to 13, inclusive, it will be seen that the clamp 38 is a U-shaped member mounted on a box-like carrier 39. The base of member 39 is apertured to receive two studs 40 which in turn project through apertures in clamp 38 and carry the clamp plate 38x. 10 By means of a spring 38xx the clamp plate 38x is normally held in the position of Figure 13. Studs 40 are connected by a supporting plate 41. Box member 39 is given support by an arm 42 on a shaft 42x carried by the turret. Pivoted 15 to box member 39 is one end of a lever 43 on a shaft 44. At the opposite end shaft 44 carries a plural-arm lever 45, one arm carrying a roller 46, and the second arm being engaged by a spring 47 (Fig. 10). The spring 47 is a release spring, whereas the roller 46 will, in the rotation of the wrapping turret, be engaged by cam surfaces (not shown) on the machine to throw the clamp into action at the proper time and to hold it in active position until the cam surfaces permit releasing action by spring 47.

The body tucker blades and their operating mechanism is shown more particularly in Fig. 8. The initial tucker blade for the short margin of the wrapper is indicated at 48. It is carried 30 by an arm 49 pivoted on a bracket 50, arm 49 having an extension 49x connected by link 51 with a lever 52. Lever 52 is pivoted on the shaft 53 connected by link 54 with a cross link 55 which in turn is connected by link 56 with a shaft 57. Secured to the end of shaft 57 is a lever arm 58 engaged by an operating rod 59. This rod will be reciprocated at the proper time by a cam (not shown).

The second tucker blade, for the wide body flap is indicated at 60. In Fig. 8 it is shown in only a partial active movement. It is carried by an arm 61 pivoted on shaft 62, the latter being held by bracket 50. Tucker blade 60 is normally retracted, this position being assured by a spring 63 engaging an arm 64, the latter with arm 61 being similar to a bell crank. The said second tucker blade 61 is operated at the proper time through a bell crank lever 65 which has a slotted end receiving a stud 61x on arm 61. Bell crank 65 is mounted on shaft 66 and is swung into operation at the proper time by a cam (not shown) on the machine.

Both tucker blades and particularly blade 60, are of thin spring steel construction and have such a compressive wiping action upon the wrapper that it is drawn tight at the corners of the package preliminary to the longitudinal seal, this enabling formation of accurate end folds and overcoming a serious difficulty in past mechanisms of the kind.

The longitudinal seam lap irons

The longitudinal seam lap irons are indicated at 67 and reference to Figures 8 to 12 inclusive will show that each lap iron is pivoted to a carrier arm 68 leading to a split sleeve 69 on a shaft 70. This shaft extends through a bearing member 71 carried by the wrapping turret and the inner end of the shaft carries a plural arm lever. 65 One arm of the lever, indicated at 72, has a roller 73 thereon controlled by fixed cam elements on the machine and the second arm 73x is engaged by a spring 74 which leads back to the turret. The active movements of the lap iron 70 75 67 are controlled by arm 72 of the lever and the

releasing movements by the spring engaging arm 73x. Each lap iron contains a heating element through which current is fed by conductor 74x from a source of current.

It will be seen from the above that the body clamp and the lap seam irons are carried by the wrapping turret, whereas the tucking irons or blades for the side seam are carried by a bracket mounted alongside the wrapping turret and in front thereof. Viewing Figure 8, it may be considered that the tucking irons are beginning their withdrawal motion and that the uppermost lap seam iron is about to descend to final down position as in the position of a like lap seam iron 67 shown at the left of the figure toward the bottom thereof. The wrapper will now be in the form shown at the right hand of Figure 15 and ready to have applied thereto closure folding tools for the bottom. As shown in Fig. 16, these folds are performed by three successive steps. By means of the opposed folding irons 75 the initial folds 76, Fig. 16, are made. Each of these two irons 75 is carried by a pair of swinging arms 77 pivoted to a bracket 78. The two pairs are connected by equalizer links 79 and 80, and the shaft 81 for one of the arms 77 may have connected thereto a lever 82 leading to actuating mechanism, such as a cam arrangement by which the folds 76 are quickly made through inward and outward movement of the iron 75. At this point, referring to Fig. 16, the bottom flap 83 is folded down as by a reciprocating blade 84, Fig. 1. The final bottom closure flap 85 projects outwardly, and in the movement of the turret flap 85 is folded down by coming into contact with a roller 86, Fig. 1, so that the package, with its bottom closed by said fold reaches station F, Fig. 1, and then moves to station G for the bottom semi-sealing operation. At this stage the plunger shown in Fig. 1b at 87 enters the arbor on which the package is held and the bottom folds are pressed against an electrically heated plate 88, immediately after which the plunger is retracted. As hereinbefore stated this semi-sealing operation is effected in somewhat less than $\frac{1}{6}$ of a second in normal commercial operation. If desired this operation may be repeated at station H. The turret then carries the arbor with its enveloping wrapper to station A for reception of the group of cigarettes from an arbor of the left hand turret.

The transfer of cigarettes to the bottom closed wrapper

As shown in Fig. 1a, a cigarette filled arbor of the cigarette feed turret will come into register with an arbor of the wrapping turret at station A. At this point a plunger 89, Figure 1a, enters the appropriate arbor of the cigarette feed turret and transfers the cigarettes into the arbor of the wrapping turret, which arbor is encircled by the bottom closed package. Although Fig. 1 does not show a stop plate for restraining the package, such a plate may be used as indicated at 90, Fig. 1a. The filled packages then are brought to position B at which time a forwardly moving plunger 91 enters the open top of the filled package on the arbor, and, pressing upon the ends of the cigarettes, transfers the filled package to a trough 92, Fig. 1c, and in registration with the tuckers 93 on shafts 94. These shafts are quickly oscillated to produce tucks in the top of the package the same as shown at 76 in Fig. 16, at the left hand side of that figure. In its progression, the top of the package then

receives the same successive end folding operations as described with respect to flaps 83 and 85 of the bottom closure, Fig. 16. As the packages advance in the trough they pass through a zone where a heated tacking iron indicated by dotted lines 90, Fig. 1, engages the top closure folds to flatten them out and lightly tack them with heat. The packages are then transferred from the initial trough into which they are placed upright with the top closure uppermost, as now described.

The package transfer mechanism

At the end of the trough 92 is a stop plate 95 which has a limited movement sufficient for the package to be received in a carrier 96 on an arm 97 carried by an oscillating shaft 98, Fig. 21. Arm 97 also carries a curved stop plate 99 adapted to restrain or hold back the succeeding package in the trough. When shaft 98 is given an active movement, a package held by a carrier 96 is moved into register with the second trough 100 and into the dotted line position P, Fig. 23. At this point a pushing plunger 101 moves the package out of the carrier, and well into the trough 100, the preceding packages being moved accordingly. In the said second trough 100 the packages receive revenue stamps and pass under a reciprocating platen 102, Fig. 1, which flattens out the stamps and each package finally reaches the end of the trough 100 ready to be transferred to the steel belt sealer and its associated devices by which the top and bottom closures of each package are securely heat sealed.

The safety lock for the package transfer

It has hereinbefore been described that when the packages have reached the end of the trough 92 they give a limited movement to a plate 95, each package in succession. Plate 95 is carried by a swinging bracket 103 and the bracket is connected to a rod 104 (Figs. 21 and 24), which leads to a latch arm 105 pivoted at 106 and having a nose or latch dog 105x, Fig. 2, in the path of a member of the mechanism which transfers the packages from the trough 100 to the belt sealer holding said transfer mechanism out of operation should, for any reason, a package not be received upon plate 95. Thus each transfer of a package to a belt sealer requires that a preceding package engage and move plate 95 at the end of the initial trough 92. To this end the transfer mechanism, for transferring packages from trough 100 to the belt sealer consists of a cam operated lever 107 pivoted at 108 is connected by link 109 to a rock lever 110 for shaft 111 (Fig. 2). Rock shaft 111, at its outer end, carries a swinging arm 112 pivoted to a package pusher 113. Between the pusher and a bracket arm 114 is an equalizing link 115. Rock arm 107 is normally pulled toward the actuating cam therefor by a spring 116.

In the position of the parts shown in Fig. 2, rock arm 107 is on the high point of the actuating cam, and latching dog 105x has been moved to the left and thus out of register with lever arm 110. It may be assumed that the foremost package in the initial trough 92 has pressed plate 95 outwardly. Thus, the latching dog 105x is held in neutral position and the transfer mechanism has been free to carry a package from the second trough 100 to the belt sealer.

If there is no package at the end of trough 92 and plate 95 lies inwardly close thereto, the latching dog 105x will be moved to vertical position and rock arm 107 will remain outwardly,

because upward movement of rock lever arm 110 is restrained by the latching dog. Hence, transfer of packages to the belt sealer will be restrained until trough 92 is completely filled with packages.

The belt sealer lies at the end of the machine at right angles to the two troughs above described, and packages semi-sealed at their ends are transferred thereto by the pusher 113, Fig. 3. Reference to the latter figure will show that upper and lower belts 120 and 121 are carried by sets of rollers 122, 123 respectively, the shafts for these rollers being mounted on a vibratory frame 124 suspended from a bracket carrier 125 which in turn is carried by an electric vibrator 126 in such a manner that the belt-carrying frame 124 and the belts are constantly vibrated during the belt-feed of the packages. Rubber blocks 125x may be placed between bracket 125 and vibratory frame 124. The right hand upper belt carrying roller 122 is on a shaft carrying a sprocket 127 engaged by a chain belt 128, which chain is led over a sprocket on the shaft for the lower right hand belt carrying roller 123 and then is led to a driven sprocket 129 and over an idler roller 130 back to sprocket 122. Sprocket 129 is driven by a series of reducing drives from motor shaft 130.

The belts are of steel tape, preferably about ten-thousandths of an inch thick, that have been butt welded to make them endless without any apparent joint, so that the belts are perfectly smooth and flat throughout their entire length. They are associated with lateral package guide rails 140, Fig. 27.

Contacting with the lower length of the upper belt, and the upper length of the lower belt, are electrical heaters 131. These heaters are carried by brackets 132 on frame 124, the brackets being U-shaped, each bracket leg carrying a small guide or supporting roller 133 engaging the adjacent belt length.

The belt sealer is driven by an independent motor and runs continuously regardless of the machine proper. Throughout the travel of the packages from the point of entry to the point of discharge, at the belt sealer stage, the vibrating and heated belts flatten down the top and bottom closure folds and serve to finally seal the packages except for a succeeding step now to be described.

Final sealing and chill assembly

The packages leaving the belt sealer pass between two air-cooled units, Fig. 3, of like construction and as shown at 134. Each unit 134 is formed with a longitudinal trough, and centrally thereof is a shallow rib. Each unit is provided with heat-conducting plates 134x, and a blower 135 is provided to force cooling air between such plates, the latter being spaced. The shallow ribs, shown best in Fig. 28 at 134xx, overcome a difficulty found in final sealing of the top and bottom closure flaps, i. e., the edge rigidity of the package resists ideal sealing pressure on the flaps at intermediate areas of said flaps at the top and bottom of the package. Inasmuch as the packages leave the belt sealer with the adhesive still hot from the heated belts, final sealing and cooling, in the manner described, result in a perfect seal.

The method of heating the lap seam irons

Referring to Fig. 1, it will be seen that shaft 135 carries a "collector ring" which rotates with the turret, it being shown at 136. This "collector ring" receives current from a brush 137 fed by

conductor 138 from a source of electric energy. As shown in Fig. 1, the "collector ring" is electrically connected with each one of the side seam sealers 67 by wire conductors. In practice, the "collector ring" may be insulated from the wrapping turret shaft and the lap seam irons may be grounded to the turret, and thence to the turret shaft and base.

The wiring diagram

In Figure 17 a suitable arrangement is shown from which it will be seen that the tractor sealer heating units 131 may receive the full voltage of the line, whereas by a variable voltage transformer, followed by a low voltage transformer, the lap seam and top and bottom heating units may be operated at or about 12 volts. A limit switch is provided, as indicated in said Figure 17 so that when power to the machine driving motor is switched off temporarily it may be mechanically connected to the limit switch so that the latter is thrown open and the current shunted through an 8 ohm resistor which, through the low voltage transformer, will cut the voltage down to say 7.0 volts which will be sufficient to keep the said heating irons against such a temperature drop as to render them not immediately operative when the machine is again thrown into action and at the same time prevent them from over-heating. Figure 17 is largely diagrammatic and no attempt has been made to show the intricate wiring and electrical assembly between the photo-electric unit and the feed-correction motor control for member 21 of the planetary assembly.

While in Figures 1 and 2 I have shown the web fed from a roll web material supported above the machine, it will be understood that the web may lead down to the base of the machine over and between a series of idler rolls down to a large supply roll near the floor or machine base for easy handling. Also, I have found that the rolls 6x and 6 may, as to one, be provided with shallow annular spaced beads and the other with corresponding channels so as to form marginal beads in the web material as it is fed by said rolls for the purpose of stiffening the web and insuring its free passage through the cutter throat, and these beads may be placed at the marginal fold lines of the wrapper sheets cut from the web.

Having described my invention, it will be understood that various modifications may be made in the form and arrangement of the various mechanical and electrical elements without departing from the spirit of the invention, what I claim and desire to secure by Letters Patent being as follows:

1. In a machine for wrapping cigarettes and the like, a rotary turret carrying open end arbors, means for feeding a wrapping sheet into register with an appropriate one of the arbors, means for wrapping the sheet about said arbor with a lap longitudinal margin formation, the sheet carrying a heat-sealing compound on one face thereof, a plurality of reciprocable heating irons on the turret, one for each arbor, each iron being formed with a chamber receiving an electrical heating resistance-member, means for moving said heaters each into heating relation to a lap seam formation of a wrapper on an appropriate arbor during a partial rotation of said turret, means for producing multiple folds at the bottom end of each longitudinally seamed wrapper on its arbor, means for applying rapid application of heat and pressure to said bottom folds to preliminarily tack the same, means for releasing the

11

lap seam heating members in succession, and means for successively projecting assemblies of cigarettes from the arbors and against said preliminarily tacked bottom folds of the wrappers thereby discharging the thus filled open top packages, a receiving member for said discharged packages, means for producing multiple folds in the top of each package means for tacking said top folds whilst the package is supported in said holding medium and means for conveying the packages to a point of discharge, in combination with means for applying heat and pressure in said conveying movement for a time dwell completely sealing said top and bottom folds.

2. A machine for wrapping cigarettes and the like constructed in accordance with claim 1, in combination with means for imparting vibrational movement to the packages by the heat and pressure means applied to the top and bottom folds in said conveying movement of the packages to the point of discharge.

3. A machine for wrapping cigarettes and the like constructed in accordance with claim 1 in combination with means for conveying the packages to a point of discharge by means of elements exerting heat and pressure on the top and bottom folds, in combination with heat-absorption pressure elements at the discharge point for the packages, the latter elements being adapted to engage and press upon the top and bottom folds in an intermediate line area well inwardly of the major side walls of the package.

4. A machine for wrapping cigarettes and the like constructed in accordance with claim 1 in which the means for applying rapid application of heat and pressure to said bottom folds to preliminarily tack the same consists of a heated plate in register with the arbors as they are moved on and with the turret, a plunger plate, and means for rapidly reciprocating said plunger plate into and out of the arbors in succession and into contact with the bottom folds of successive packages on said arbors.

5. In a machine for wrapping cigarettes and the like, a rotary turret carrying open end arbors, means for feeding a wrapping sheet into register with an appropriate one of the arbors, means for wrapping the sheet about said arbor with a lap longitudinal margin formation, the sheet carrying a heat-sealing compound on one face thereof, a plurality of reciprocable heating irons on the turret, one for each arbor, each iron being formed with a chamber receiving an electrical heating resistance-member, means for moving said heaters each into heating relation to a lap seam formation of a wrapper on an appropriate arbor during a partial rotation of said turret, means for producing multiple folds at the bottom end of each longitudinally seamed wrapper on its arbor, means for applying rapid application of heat and pressure to said bottom folds to preliminarily tack the same, means for releasing the lap seam heating members in succession, and means for successively projecting assemblies of cigarettes from the arbors and against said preliminarily tacked bottom folds of the wrappers thereby discharging the thus filled open top packages, a receiving member for said discharged packages means for producing multiple folds in the top of each package, means for tacking said top folds, means for successively turning the packages approximately 90°, means for pushing the packages in succession between upper and lower heated metallic belts adapted to completely seal the top and bottom closure folds.

12

6. A machine for wrapping cigarettes and the like constructed in accordance with claim 5, in which the means for successively turning the packages approximately 90° consists of a lever having a U-shaped package receiving member and an overlying guard plate to form a stop for packages back of that being transferred, in combination with a movable stop plate for that package which is brought into turning position, said stop plate being movable, and means including said movable stop plate for controlling the means for pushing the packages into succession between the upper and lower heated metallic belts.

7. In a machine for wrapping cigarettes and the like constructed in accordance with claim 5, in combination with a movable stop plate in front of the means for successively turning the packages, said plate being moved by each package as it reaches position for turning, the means for pushing the packages into succession between the upper and lower heated metallic belts consisting of a pusher plate, a reciprocable lever for actuating said plate, a rotary cam having a high point for actuating said reciprocable lever, latch means normally holding the reciprocable lever and the cam lever in neutral position, and means intermediate said stop plate and said latch means whereby the latter is released upon movement of the stop plate by a cigarette package brought to turning position.

8. A machine for wrapping cigarettes and the like constructed in accordance with claim 1 in which the means for wrapping the sheets about the arbors on the rotary turret consists, for each arbor, of a U-shaped clamp, in combination with two flexible blades, and opposed levers adapted to actuate said blades with wiping action upon the opposite sides of the sheet preliminary to movement of the reciprocable heating iron into movement against the lap side seam provided by the action of said flexible blades, and means for retracting said blades.

9. A machine for wrapping cigarettes and the like constructed in accordance with claim 1 in combination with heat absorption pressure elements at the point of discharge of the packages, said elements consisting of upper and lower members having opposed troughs abutting the top and bottom folds of the packages, each trough being formed with a central longitudinal rib adapted to engage and press upon the abutting folds in an intermediate line area inwardly of the major side walls of the package, said troughs being carried by heat radiation elements.
